UNITED STATES PATENT OFFICE.

GEORGE E. MARLATT, OF PASADENA, CALIFORNIA, ASSIGNOR TO MERGENTHALER LINOTYPE COMPANY, A CORPORATION OF NEW YORK.

TYPOGRAPHICAL MACHINE.

Application filed October 27, 1919. Serial No. 333,763.

To all whom it may concern:

Be it known that I, GEORGE E. MARLATT, a citizen of the United States, residing at Pasadena, county of Los Angeles, State of California, have invented a new and useful Improvement in Typographical Machines, of which the following is a specification.

My invention relates to machines in which character-matrices stored in a magazine are released by the operation of keys, and has for its purpose to provide means whereby a minimum number of keys may be made to control the release of a maximum number of character-matrices. Applied to linotype machines, as herein shown, it permits of the release of matrices from an auxiliary magazine and in addition matrices of irregular layout, such as small-capital character matrices stored in the primary magazine, to be controlled by the group of "lower-case" keys at the left-hand side of a linotype keyboard.

The accompanying drawings illustrate my invention in its application to a linotype machine. While I thus show a preferred embodiment of my invention, it is to be understood that many changes and variations may be made therein and in its adaptation to various types of key-controlled machines without departing from its scope. I therefore desire to be understood as not limiting myself to any specific form of embodiment in its application.

Figure 1 is an explanatory front view of a linotype machine showing the relationship of the keyboard and keyrods to the primary and auxiliary magazines.

Figure 2 is a fragmentary rear view of the keyrods shown in Figure 1, showing my invention applied thereto.

Figure 3 is a plan view of the keyrod guides showing the master or "lower-case" keyrods shifted and connected to operate the keyrods controlling the release of small-capital letters.

Figure 4 is a plan view similar to Figure 3 showing the master keyrods connected to control the keyrods associated with the auxiliary magazine.

Figure 5 is a plan view of the keyrod guides showing the "lower-case" keyrods in normal position to release the lower-case matrices.

Figure 6 shows the construction of mecha-

nism for shifting the keyrods with relation to the matrix escapements.

Figure 7 is an elevation of Figures 3, 4 and 5 and shows means for manually connecting and disconnecting the rock shafts with relation to the keyrods and certain of the keyrods with relation to the escape- 60

ments.

Figure 8 is a right-hand view of the key-rod system.

Figure 9 shows the manner of imparting motion from the master keyrods to the trans- 65 verse rock-shafts connecting the several groups of keyrods, and from the rock-shafts to the other groups of keyrods.

Figure 10 shows the manner of limiting the radius of action of the connecting rock- 70 shafts.

Similar reference characters indicate similar parts throughout the several figures of the drawings. Corresponding letters of the alphabet are used as reference characters for 75 the "lower-case" or master keys and similar letters with exponents designate the parts controlled by the master keys.

Heretofore linotype machines equipped with an auxiliary magazine at the side of the primary magazine have been provided with a secondary keyboard for controlling the release of matrices from the auxiliary magazine. Such an arrangement is shown in patent to Muhleisen, No. 608,067, granted 80 July 26, 1898. In the present invention transverse rock-shafts are operated by the group of keyrods at the left of the standard keyboard and in turn operate the keyrods which release the matrices from the auxiliary magazine.

The group of keyrods 3 for releasing the matrices from the primary magazine 1 and the group of keyrods 4 for releasing the matrices from the auxiliary magazine 2 are 95 supported and guided in an outer open frame comprising a supporting rock-shaft 5, side members 6 and a top plate 7 having perforations therein for spacing apart and guiding the individual keyrods. The rock- 100 shaft 5 is supported in a fixed frame 8, the side members contacting therewith to prevent sidewise movement of the keyrod groups.

The outer frame above described supports and encompasses an inner frame comprised 105 of a lower member 9 and upper member 10

connected by side members 11 which carry a series of horizontal rods 12 designed to connect selected groups of the vertical key-rods 3-4 one with another for accomplishing the purposes of this invention. For this purpose the inner frame is shiftable sideways in the outer frame, being slidable therein on pins 13 secured in the side members of the inner frame and bearing in notches 18 in the side members of the outer frame. The inner frame is shiftable manually by means of a handle 14 projecting from a vertical shaft 15 bearing in the upper and lower members of the inner or shiftable frame and having an eccentric point 16 bearing in the upper member 7 of the outer and relatively stationary frame. The eccentric point 16 being thus confined, movement of the handle 14 causes the inner frame and groups of rods to be moved to the right or left as desired as the handle is moved in an opposite direction. Each horizontal rock-shaft 12 in the inner frame is provided with three arms, one of which is acted upon by the associated "lower-case" keyrod to rock the shaft, a second one for operating an associated keyrod for releasing a corresponding small-capital letter-matrix when the first arm is acted upon as described, and a third arm for operating an associated keyrod of the group connected with the auxiliary magazine to release a corresponding letter-matrix when the first arm is acted upon by the "lower-case" keyrod when the associated key is touched.

Movement of the handle 14 to the extreme right as shown in Figure 5 causes the inner frame to be moved to the extreme left, which may be considered its normal position as the "lower-case" keyrods are then in position to release only the "lower-case" letter-matrices from the primary magazine and the arms on the "lower-case" ends of the rock-shafts are out of engagement with their associated keyrods. Each "lower-case" keyrod has an arm or spur N² for operating the arm on the associated rock-shaft. When the inner frame is moved to the normal position as shown in Figure 5 the arms of the rock-shafts are moved to one side of the arms on the keyrods, so that operation of the keyrods will not affect the rock-shafts.

Movement of the handle 14 to a central position as shown in Figure 3 places the right-hand edge of an arm N⁴ in engagement with the arm N² on the corresponding keyrod N¹. The same movement of the frame places the central arm N⁷ on the rock-shaft beneath the spur N⁶ on the associated small capital keyrod N⁵, and when the "lower-case" keyrod is operated the rocking of the shaft causes the small-capital keyrod N⁵ to be raised and the proper matrix to be released from the magazine 1. Further movement of the inner frame to the position

shown in Figure 4 places the left-hand edge of the arm N⁴ on the shaft N³ in engagement with the spur N² on the keyrod N¹, moves the central arm N⁷ from beneath the arm N⁶ on the small-capital keyrod N⁵ and places the third arm N¹⁰ beneath the spur N⁶ on the keyrod N⁸ in the group 4 connected with the auxiliary magazine 2, so that operation of the "lower-case" key will release a corresponding matrix from the auxiliary magazine.

While the foregoing description is confined to the several parts associated with the release of variations of but one character in the magazines, it also applies to the release of the other characters represented on the keyboard.

When it is desired to assemble small-capital letter-matrices or those from the auxiliary magazine, it is first necessary to disconnect the "lower-case" keyrods 3 from the escapements, so that matrices will not be released from both groups at the same time. This group of keyrods is therefore independently guided in a plate 17 slidable on the continuous plate 7 which guides the whole series of keyrods. Cam-slots 18 in the shorter plates are acted upon by pins 19 passing through slots 20 in the continuous plate 7. The pins 19 are carried by the upper member 10 of the inner frame which is movable as described. The movement of the frame member 10 to the extreme left position causes the short plate to move the "lower-case" keyrods to a position beneath the escapements 21 of the primary magazine, while movement in the opposite direction disconnects the rods from the escapements, as indicated in broken lines in Fig. 8. The lower ends of the keyrods are held against movement by a guide plate (not shown) common to linotype machines, this plate serving to retain the lower ends of the rods in position when the upper ends are moved as described. The keyrods have a vertical upward stroke to release the matrices when the keys on the keyboard are depressed. The keyboard mechanism for causing this action need not differ from that common to linotype machines.

A group 22 of keyrods controlling the release of the punctuation points must be connected with the escapements of the primary magazine when either "lower-case" or small-capital letter matrices are to be released from the primary magazine, but must be disconnected when the auxiliary magazine is in use. This group of keyrods are therefore made automatically shiftable according to the position of the operating handle 14. A guide plate 23 is connected by means of a lever 24 to the eccentric end 16 of the operating shaft 15. When the inner frame is moved as described to operate the auxiliary magazine 2 the movement of the operating

- shaft 15 causes the plate 23 to withdraw the small group of keyrods as shown in Figure 4, thus disconnecting the keyrods 22 from the escapements of the primary magazine 1. 5 In either of the other positions of the frame heretofore described and shown in Figures 3 and 5, the group 22 of keyrods controlling the punctuation points is moved to a position beneath the escapements of the primary 10 magazine for use in connection with either "lower-case" or small-capital letter-matrices 27.
- It will be noted that on the keyboard the same keys which control the release of the 15 small-capital letters also control the release of other characters, such as figures, diphthongs, triphthongs, etc., the two characters in each case being represented on the same matrix, in the manner well known in the 20 art. In this invention, when the small-capital keyrods are connected for operation from the "lower-case" keys, the release of these duplex-matrices in the usual manner is not interfered with. When the handle has been 25 moved to connect the small-capital keyrods with the "lower-case" keyrods either the "lower-case" keys or the small-capital keys may be used to release the small-capital 30 matrices.
- 35 The inner shift frame with the system of horizontal rock-shafts may be readily removed to provide access to the vertical keyrods or for other purposes. The lower and upper members of the frame are secured to the side members by connecting arms 26, screws 25 joining the upper and lower connecting arms to the upper and lower members of the frame respectively. In order 40 to remove the frame the screws 25 are withdrawn, and the frame is lifted backwards and upwards out of the notches 28 in the outer frame. The upper member 10 of the inner frame may retain its usual position when the side members are thus removed, 45 being supported by the upper plate 7 of the outer frame through the instrumentality of the pivot screw 29, the pivot arm 24 and other parts. Likewise the lower member 9 of the inner frame may in such case drop 50 to a position of rest upon the stationary frame 8. In order to restore the frame to position it is desirable that the inner frame be inserted in the normal position heretofore described, so that the arms in the rock-shafts will not interfere with the arms on the keyrods when the frame is being seated in the notches of the outer frame. The 55 same result may be accomplished by slightly raising all but the lower-case keyrods. This 60 may be accomplished by inserting a sword 30 beneath the keyrods, one such sword being used for the keyrods associated with the auxiliary magazine 2 and another for those associated with the primary magazine. In 65 such case it is necessary to first disconnect
- all of the keyrods from their escapements. This may be accomplished by means of a handle 31 connected to the outer frame by means of a link 32, this arrangement being substantially the same in construction and 70 operation as that shown in my Patent No. 1,266,970, dated May 21, 1918. In order that the arms N^4 on the shafts N^3 may retain their normal position when the frame is removed as above described each end of 75 each rock-shaft is provided with a slot or clearance 33 through which is inserted a rod 34, the clearances 33 being sufficiently large to permit the necessary movement of the rock-shafts, but limiting their movement in 80 both directions. Certain of the shafts may project through the side members of the inner frame a sufficient distance to receive retaining pins 35, thus keeping the side members in position when the upper and lower 85 members of the frame are removed as and for the purpose described.
- In operation, the structure described functions as follows to accomplish the purposes of this invention: With the parts in normal position as shown in Figure 5, an operator desiring to assemble small-capital letters would move the handle 14 to the position shown in Figure 3. This movement of the handle causes the inner frame to 90 move to the right, the pins 19 carried by the moving frame acting in and upon the cam-slots 18 to force the upper keyrod guide 17 to be retracted and thus disconnect the "lower-case" keyrods 3 from their escape- 95 ments 21. This same movement of the inner frame carries the arms N^4 on the rock-shafts N^3 to a position above the arms N^2 on the keyrods. Simultaneously the arms N^7 on the rock-shafts are placed beneath the 100 arms N^6 on the small-capital keyrods; thus when the "lower-case" keyrods are actuated by touching the "lower-case" keys the "lower-case" keyrods will rise, causing the shafts N^3 to rock and the arms N^7 to raise 105 the small-capital keyrods, releasing from the magazine the selected matrices, which then drop to the assembler-belt 36 and are carried to assembling position in the usual manner. It will be noted that the movement of the 110 handle 14 from the normal position shown in Figure 5 to the position shown in Figure 3 does not affect the position of the small shift-plate 23 controlling the key-rods 22 associated with the punctuation points, these key-rods retaining their operative position with relation to the escapements of the primary 115 magazine.
- If it is desired to release matrices from the auxiliary magazine 2 the handle 14 is 120 moved to the position shown in Figure 4. It will be seen that the position of the inner frame thus obtained leaves the "lower-case" shift plate 17 in the same position as when the handle is in the position shown in Fig- 125 130

ure 3, but the shift frame is moved a greater distance to the right, leaving the arms N^4 still in engagement with the "lower-case" keyrods but moving the arms N^7 out of engagement with the small-capital keyrods and placing the arms N^{10} in position beneath the arms N^9 on the auxiliary keyrod system. Operation of the "lower-case" keys will then release matrices from the auxiliary 10 magazine.

This latter movement of the handle 14 to the position shown in Figure 4 causes the eccentric point 16 of the operating shaft 15 to engage the pivot lever 24 and retract the shift plate 23 which controls the keyrods 22 associated with the punctuation points, thus disconnecting this group of keyrods from the escapements of the primary magazine, and permitting their utilization for releasing the punctuation points from the auxiliary 20 magazine 2.

Having thus described my invention, what I claim as new and desire to secure Letters Patent for, is:

25 1. In a typographical machine, in combination, a matrix-containing magazine, escapements for releasing the matrices in said magazine, keyrods for operating said escapements, means for connecting and disconnecting all of said keyrods with and from all of 30 said escapements, and other means for disconnecting and connecting a limited group of said keyrods from and with a contiguous group of said escapements and respectively connecting and disconnecting them with and from a non-contiguous group of said 35 escapements.

40 2. In a typographical machine, the combination of a magazine containing a group of matrices arranged in one order as to character and a second group of matrices arranged in a different order as to character, a keyboard, and means whereby a given group of finger keys may be connected to 45 either group of matrices, as desired, notwithstanding their different character arrangement.

50 3. In a typographical machine, the combination of a magazine containing groups of matrices, those of one group being arranged in one order as to character and those of another group in a different order as to character, escapements controlling the release of the matrices from the magazine, a 55 series of key-controlled actuating rods for the escapements, and means whereby the actuating rods for the escapements of the first-mentioned group of matrices may be disconnected therefrom and connected to the 60 actuating rods for the escapements of the second-mentioned group, when desired.

65 4. In a typographical machine, the combination of a primary magazine containing two groups of matrices, an auxiliary magazine containing a further group of matrices,

a keyboard common to both magazines, and means whereby a given group of finger keys of said keyboard may be connected to any one of three groups of matrices, as desired.

5. In a typographical machine, the combination of an escapement actuating rod, and two manually operated finger keys operatively connected to said rod. 70

6. In a typographical machine, the combination of two escapement actuating rods, 75 two finger keys, one connected to each of said rods, and means whereby one of the finger keys may be disconnected from its actuating rod and connected to that of the other key, when desired. 80

7. In a typographical machine, the combination of a group of escapement actuating rods, and two corresponding groups of manually operated finger keys, both operatively connected thereto. 85

8. In a typographical machine, the combination of two groups of escapement actuating rods, two corresponding groups of finger keys operatively connected thereto, and means whereby one group of finger keys may 90 be disconnected from its corresponding group of actuating rods and connected to the other group of actuating rods, when desired.

9. In a typographical machine, the combination of three groups of escapements, a common group of finger keys, and means whereby said group of finger keys may be operatively connected to any selected group of escapements to the exclusion of the others. 100

10. In a typographical machine, the combination of three or more groups of escapement actuating rods, a group of finger keys operatively connected to one of said groups, 105 a second group of finger keys, and means whereby said second group of finger keys may be operatively connected to any selected group of escapement actuating rods, as desired.

11. In a typographical machine, the combination of three or more groups of escapement actuating rods, a group of finger keys operatively connected to one of said groups, a second group of finger keys, means whereby said second group of finger keys may be 115 operatively connected to any selected group of escapement actuating rods, as desired, and automatic means for disconnecting certain of the keys of the first-mentioned group from the corresponding actuating rods when the second-mentioned group of keys is operatively connected to a given group of actuating rods. 120

12. In a typographical machine, the combination of a primary magazine and an auxiliary magazine, each provided with escapements, a keyboard normally connected to the escapements of the primary magazine, and means whereby a given group of finger keys of said keyboard may be disconnected 125 130

from the corresponding escapements of the main magazine and connected to other escapements of said magazine or to the escapements of the auxiliary magazine, as 5 desired.

13. In a typographical machine, the combination of a primary magazine and an auxiliary magazine, each provided with escapements, a keyboard normally connected 10 to the escapements of the primary magazine, means whereby a given group of finger keys of said keyboard may be disconnected from the corresponding escapements of the main magazine and connected to other escapements 15 of said magazine or to the escapements of the auxiliary magazine, as desired, and automatic means acting when said group of finger keys is connected to the escapements of the auxiliary magazine to 20 disconnect other keys of the keyboard from the corresponding escapements of the main magazine.

14. In a typographical machine, the combination of two magazines arranged in 25 tandem, and each having escapements to control the release of matrices therefrom, a series of key-controlled actuating rods for the escapements of one magazine, a second series of actuating rods for the escapements 30 of the other magazine, connections between corresponding actuating rods of the two series, means for making and breaking said

connections at will, and automatic means for shifting the affected actuating rods of one series out of and into operative relation 35 to their corresponding escapements as said connections are made and broken, respectively.

15. In a typographical machine, the combination of two magazines arranged in 40 tandem, and each having escapements to control the release of matrices therefrom, a series of key controlled actuating rods for the escapements of one magazine, a second series of actuating rods for the escapements 45 of the other magazine, rock shafts connecting the corresponding actuating rods of the two series, a shift frame wherein the rock shafts are mounted and adjustable to make or break said connections at will, and means 50 controlled by the adjustment of said shift frame for shifting the affected actuating rods of one series out of and into operative relation to their corresponding escapements as said connections are made and broken, re- 55 spectively.

In testimony whereof I have hereunto set my hand this 18th day of October, 1919, in the presence of two attesting witnesses.

GEORGE E. MARLATT.
